United States Patent [19]
Armstrong et al.

[11] Patent Number: Des. 314,597
[45] Date of Patent: ** Feb. 12, 1991

[54] LOW IMPACT STAIR CLIMBING EXERCISE APPARATUS

[75] Inventors: **Timothy O. Armstrong**, Bellevue, Wash.; **John W. Bull**, Irvine, Calif.; **David B. Smith**, Bellevue, Wash.

[73] Assignee: **Precor Incorporated**, Bothell, Wash.

[**] Term: **14 Years**

[21] Appl. No.: **307,373**

[22] Filed: **Feb. 9, 1989**

Related U.S. Application Data

[63] Continuation-in-part of Ser. No. 109,103, Oct. 21, 1987, Pat. No. D. 304,358, which is a continuation-in-part of Ser. No. 12,119, Feb. 6, 1987, Pat. No. D. 302,451.

[52] U.S. Cl. **D21/195**

[58] Field of Search **D21/191-199; 272/69, 70, 72, 97, 129, 134, 70.2, 130**

UNITED STATES PATENT AND TRADEMARK OFFICE
CERTIFICATE OF CORRECTION

PATENT NO. : Des. 314,597

DATED : February 12, 1991

Page 1 of 5

INVENTOR(S) : Timothy O. Armstrong et al.

It is certified that error appears in the above-identified patent and that said Letters Patent is hereby corrected as shown below:

On the title page:

The title page showing the illustrative figure should be deleted to appear as per the attached title page.

Sheets 1-3 of the drawings should be deleted to be replaced with Sheets 1-3 of drawings, consisting of Figs. 1-6, as shown on the attached pages.

Signed and Sealed this
Seventh Day of January, 1992

Attest:

HARRY F. MANBECK, JR.

Attesting Officer
